UNITED STATES PATENT OFFICE.

LESLIE WINFIELD GATCHELL, OF NEWBERG, OREGON.

BILLING-CARD.

1,191,582.

Specification of Letters Patent. Patented July 18, 1916.

Application filed August 10, 1915. Serial No. 44,703.

To all whom it may concern:

Be it known that I, LESLIE W. GATCHELL, a citizen of the United States, and a resident of Newberg, in the county of Yamhill and State of Oregon, have invented a new and useful Improvement in Billing-Cards, of which the following is a specification.

The object of my invention is to provide 10 a self-addressed billing card, such as used by light and power or companies using a monthly statement system, by the use of which an envelop for the bill is made unnecessary.

15 A further object of my invention is to provide such a bill which will form its own envelop when originally sent to the customer, and will also be self-inclosing and self-addressing, when returned to the customer as 20 a receipt, after the bill has been paid and the stub detached for the files of the company.

With these and other objects in view, my invention resides in the construction, combination and arrangement of parts to be hereinafter described and claimed, and illustrated in the accompanying drawings forming a part of this specification, in which like reference characters indicate like parts 30 throughout the several views.

Figure 1 is a plan view of my improved billing card in its open position. Fig. 2 is a view of the card folded and ready to be sent to a customer. Fig. 3 is a view of the 35 card folded for mailing after the stub has been detached. Fig. 4 is a longitudinal section on the line 4—4 of Fig. 2. Fig. 5 is a longitudinal section on the line 5—5 of Fig. 3.

40 Referring to the drawings, the billing card is shown at A, consisting of a strip of suitable paper or cardboard scored transversely, through its center as shown at 1, so that it may be readily folded in half. A portion 2 of one end of the card is separated from the main strip by perforations or indentations 3, so that it may be readily torn off. This stub 45 is suitably marked to form the record kept by the company in its files. The remaining 50 part of the card strip forming the bill proper is scored transversely through its center as shown at 4, forming the two sections 5 and 6 which are suitably ruled to form a blank

statement of account to be filled in and sent to a customer. 55

An opening 7 of suitable size and shape is formed in the lower portion of the end section 6, and the lower portions of stub 2 and section 5 are ruled as shown at 8 and 9 respectively, to receive the name and address 60 of the sendee, in such a position as to allow the name and address to show through the opening 7 when the card is folded upon the line 1 or 4.

The back of the card is provided in the 65 upper right hand corner with a place 10 for a postage stamp when folded upon either the line 1 or 4. A gummed sticker 11 is used to fasten the ends of the card together when folded in either position. 70

From the foregoing the operation and use of my device will be apparent. The name of the sendee is written in the spaces 8 and 9 and the monthly statement of the sendee's bill is written upon the sections 5 and 6, a 75 suitable record of the bill being also written on the stub. The bill is then folded on line 1, fastened by a sticker 11 and mailed, the address written in the space 8 showing through the opening 7. After the bill has 80 been paid and the stub detached for the files of the sending company, the bill is folded on line 4 and again fastened by a sticker, and mailed to the sendee as a receipt, the address written in space 9 now showing 85 through the opening 7.

It will thus be seen that I have provided a billing card which is self-addressing and self-inclosing when originally sent to a customer, and also when returned to the customer as a receipt after the bill is paid and the stub detached. 90

I claim:—

1. A billing card of the character specified comprising a strip perforated transversely 95 near one end to form a detachable stub and a bill proper, the entire strip and the bill proper being each scored transversely through their centers to form folding lines for the card, the bill proper having an opening in the end thereof opposite the stub, an address portion on the said stub and on the end of the said bill proper opposite the said opening, the said address portions lying beneath the said opening when the entire 100 strip and when the bill proper only are 105

folded centrally respectively, and means for fastening the ends of the folded card.

2. A billing card comprising a bill proper and a detachable stub shorter than the bill proper, the bill proper having an address exposing window in its end opposite the stub, an address space upon the stub and upon the end of the bill proper opposite the

said window, the said address space adapted to lie beneath the said window when the entire billing card and when the bill proper only are folded once centrally.

LESLIE WINFIELD GATCHELL.

In presence of—

C. R. CHAPIN,
R. J. MOORE.
